A technical drawing of a three-stage filter assembly. The assembly consists of three vertical filter canisters, each with a top cap featuring a circular port. The top cap of the middle filter is labeled with a circled '15' and a circled '11'. The top cap of the bottom filter is labeled with a circled '11'. The bottom cap of the middle filter is labeled with a circled '15'. The bottom cap of the bottom filter is labeled with a circled '11'. The filter canisters are supported by a central vertical frame. Various parts are labeled with numbers: 19, 20, 16, 23, 14, 13, 24, 12, 22, 25, 9, 19, 20, 21, 18, and 20. The drawing uses fine lines and cross-hatching to indicate the internal structure and assembly of the filter stages.

CARDING, CLEANING, OPENING, AND LIKE
MACHINE FOR TEXTILE FIBERSRudolf Setzer, Munich-Trudering, Germany, as
assignor to Technik & Investment Aktiengesell-
schaft, Vaduz, LiechtensteinApplication November 1, 1933, Serial No. 696,258
In Germany November 4, 1932

11 Claims. (Cl. 19—99)

Carding, cleaning and opening cylinders for textile fabrics with radial or nearly radial teeth are in some cases liable to damage the fiber, and to avoid this the clothing used in some machines has teeth which are more or less tangential with respect to the circumference of the cylinder or drum. In some cases there are two coacting cylinders, and in others a cylinder works eccentrically within an external system of teeth. The degree of accuracy required in constructing and adjusting such machines is so great that wide adoption thereof has proved impracticable.

According to my invention at least two cylinders are used, one of which, the feed cylinder, receiving the fiber from the feed apparatus, has teeth approximately tangential to the cylinder, the teeth having outwardly facing channels, and the other cylinder, the stripping cylinder, has teeth which by relative movement of the two cylinders are caused to sweep through the channels of the teeth on the feed cylinder, stretching the fibers and ultimately dragging them away from the channeled teeth.

Preferably, the channeled teeth of the feed cylinder are gutter-shaped, and their points are formed by a tapered extension of one side wall of the channel. Alternatively each channeled tooth may have two points of equal or different lengths. The tooth may be reinforced by means of a flange or rib along its top edge, which is preferably parallel with the base. The side walls of the channel may have lugs with enlarged ends forming feet by means of which the teeth are fixed into grooves in the cylinder. The fixing of the feet may be effected by means of brackets or bars placed across them, and these may be so designed as to prevent excessive lateral or outward and inward bending.

Examples of apparatus according to the invention are shown in the accompanying drawings.

Fig. 1 illustrates diagrammatically the manner in which a channeled or gutter-shaped tooth on the feed cylinder cooperates with a pointed conical tooth on the stripping cylinder, and

Fig. 2 is a similar view, showing a channeled or gutter-shaped tooth on the feed cylinder cooperating with saw teeth on the stripping cylinder.

Figs. 3 to 5 are views of a preferred form of channeled tooth, and

Fig. 6 shows a modification in which the tooth has two points.

Fig. 7 is a cross section of part of a feed cylinder with channeled teeth, and

Fig. 8 is an elevation thereof, viewed from the left of Fig. 7.

Figs. 9, 10 and 11 illustrate successive stages of the operation by which a channeled tooth on the feed cylinder collects a tuft or tussock of fiber and coats with a pointed conical tooth on the stripping cylinder, and

Fig. 12 illustrates one stage of this operation with saw teeth on the stripping cylinder.

Fig. 13 is a vertical section of an opening machine with a pair of cylinders having teeth in accordance with the invention.

Fig. 14 is a vertical section of a machine as shown in Fig. 13 but equipped with two stripping cylinders, and

Figs. 15 and 16 illustrate an arrangement of bent saw teeth on the stripping cylinder.

Referring first to Figs. 1 and 2, 5 designates a channeled or gutter-shaped tooth on the feed cylinder having a point *a*. When the point or tip *a* engages the fiber a coil *f* of fiber is formed thereon, and slips onto the tooth to a position such as that indicated at *b*, travelling through the distance *s*. By slipping on to the thick shank *s* the fiber is loosened or stretched very considerably, and the fiber may indeed become parted.

The tooth 5 is of gutter shape, with a channel *h* into which teeth 7 in the form of conical pins on the stripping cylinder as shown in Fig. 1, or in the form of saw teeth 26 on the stripping cylinder as shown in Fig. 2, can engage. If a tooth 7 engages the channel of the gutter-shaped tooth 5, as indicated in Fig. 1, and the two teeth were travelling as indicated by arrows, with velocity *v* of the gutter-shaped tooth 5 on the feed cylinder equal to velocity *v*₁ of the pin tooth 7 on the stripping cylinder, the two teeth would move together like two teeth of a spur gear, and the tooth 7 could not move the fiber coil to position *b* but if velocity *v*₁ is smaller than *v* the coil can slip along the tooth 5 at a rate depending on the difference between the velocities, and this difference can be made of any value required. The rate at which the fiber coil is stretched can therefore be made quite independent of the rate of travel of the tooth 5. The stretching of the fiber coil can be accelerated by reversing the direction of movement of the tooth 7.

The teeth 7 or 26 are shaped and arranged so that they not only regulate the stretching of the fiber coil, but also remove the fibers from the tooth 5. Some of the fibers engaged by the tooth 5 form coils round its tip and are slid along the tooth, towards the thick end, being thereby

stretched. Other fibers, clinging to the tooth but loosely distributed, are dragged by the teeth 7 or 26 into the channel h, and pulled through the same, so that they also undergo stretching.

5 A form of tooth suitable for the feed cylinder or feed drum is shown in Figs. 3, 4 and 5. This tooth is tangentially disposed with reference to the cylinder and has a body portion 8 with two wall or side portions 9 and 10, forming a channel 10 open on the side facing outwards. The part 10 is longer than the parts 8 and 9 and tapers to a point 11. The straight top edge of this part has a reinforcing flange 12. The parts 9 and 10 have lugs 13 and 14, to which are joined the arcuate feet 15 and 16 of the tooth.

Fig. 6 shows a modification in which the part 9 is also tapered to a point 17 but is shorter than the point of the part 10. It may, however, be of the same length, or longer.

20 The point or points 11 or 17 may be bent inwards or outwards, instead of extending in the same direction as the channel.

Figs. 7 and 8 illustrate a method of attaching to a feed cylinder teeth such as those shown in Figs. 3 to 5 and Fig. 6. 18 designates the cylinder, which has around its circumference pairs of grooves 19, 20, into which the feet 15, 16 of the teeth fit, supporting the teeth in circular alignment with each other, the teeth being attached to the cylinder by means of flanged brackets 21, 22 which are fixed by screws 23, 24. These brackets, placed in front of, and behind, the lugs 13, 14, extend over the full length of the cylinder occupied by teeth, each bracket holding down a bank of teeth. The outwardly directed flanges 25 of the brackets 22 may be so constructed (for instance by giving them recesses or projections) that they prevent excessive lateral bending or excessive outward or inward bending of the tooth points, as for example when cotton fiber containing much seed is dealt with. The brackets hold the teeth very securely, but removal of teeth for the purpose of renewal can be effected without difficulty by unfastening the screws. I may use plain flat bars instead of the flanged brackets, and may adopt other forms of feet and fastenings.

Figs. 9 to 12 illustrate the manner in which the teeth on the two cylinders coact. When a channelled tooth on the feed cylinder has engaged a tuft 27 of fiber, as shown in Fig. 9, and has carried it into proximity with a tooth 7 on the stripping cylinder, as shown in Fig. 10, the relative movement of the tooth 7 with respect to the channelled tooth, indicated by an arrow, causes the tooth 7 to pass through the channel 10, dragging with it the fiber, which clings to the tip and sides of the channel and is thus stretched and "opened" before ultimately being withdrawn from the channel. Fig. 11 shows a conical tooth 7 operating in this way, and Fig. 12 shows saw teeth 26 similar to the teeth 26 shown in Fig. 2.

Fig. 13 shows an opening machine with feed apparatus 28, 29, 30 of a well known type, including a pedal trough feed regulator. The feed cylinder 31 has teeth 8 of the kind shown in Figs. 3 to 5 and is rotated as indicated by an arrow, at a speed depending on the output and the degree of opening required. 32 is a grid. The repeated engagement of the teeth 8 with the fiber supplied by the feed roller 29 causes the same to be bent outwards slightly, as shown in Fig. 13, so that the teeth sweep past the feed roller nearly parallel with fiber presented to them by the roller. If the distance from the roller is properly ad-

justed the teeth lightly engage the layer of fiber thereon and take a portion thereof with them, without injury to themselves or the fiber. The tufts collected by the teeth 8 are carried along the grid 32 into proximity with the teeth 7 of the second or stripping cylinder 33, these teeth being shown as pins by way of example although they might also be saw teeth 26, Figs. 2 and 12. The cylinder 33 rotates either as indicated by the arrow I, or as indicated by the arrow II, but in any case there is a relative movement between the two cylinders causing the teeth 7 or 26 to sweep through the channels of the teeth 8, as hereinbefore described. The relative speed can be regulated to suit any kind of fabric which is to be dealt with.

The fiber taken by the teeth 7 or 26 from the teeth 8 is carried to the delivery end of the machine, where a stream of air created by a fan 34 carries it into a delivery duct 35, through which it passes to sieve drums and winding apparatus in the usual way.

Means other than a fan, of any suitable conventional kind, may be used for taking the fiber from the teeth 7 or 26.

Referring now to Fig. 14, this opening machine which is otherwise designed like the one illustrated in Fig. 13, has an additional or second stripping cylinder 38 at the rear of the first stripping cylinder 33, which second stripping cylinder 38 is equipped with teeth 7 or 26. For instance, the first stripping cylinder 33 may have pin teeth 7, and the second one, 38, may have saw teeth 26. In this machine, the first stripping cylinder 33 rotates in the direction of arrow II and at a velocity which is only slightly lower than that of the feed cylinder 31. The first stripping cylinder 33 takes the tufts from the teeth 8 of feed cylinder 31 and carries them upwards. The tufts are detached from the teeth of the first stripping cylinder 33 by the teeth of the second one, 38, which rotates similar to feed cylinder 31, in the direction of arrow I. The tufts are carried by the teeth of the second stripping cylinder 38, past a grid 39, to the delivery duct 35. The fibers are removed by a fan 34 as described for the stripping cylinder 33 in Fig. 13, or any other suitable means may be provided for taking the fibers from the second stripping cylinder 38. This method of using two stripping cylinders 33 and 38 may be used with advantage for fiber which requires delicate treatment but must nevertheless be thoroughly cleaned.

When the single stripping cylinder 33 shown in Fig. 13 rotates as indicated by the arrow I the opening action is energetic and rapid, and it is only in this case that the grid 36 comes into operation.

The diameter and length of the cylinders depend generally on the kind of fiber to be treated and the output required.

The channelled teeth of the feed cylinder 18 or 31 may be sufficiently wide for two or more teeth of the stripping cylinder 33 to pass through the channels side by side.

Referring now to Figs. 15 and 16, the teeth may be arranged with all of their points or ends in a single plane at right angles to the axis of the stripping cylinder, as shown for the saw teeth 26 on the stripping cylinder 33 in Fig. 15. However, if desired, and particularly if the channels of the gutter-shaped teeth are wide, the teeth may be bent laterally, as shown in Fig. 16. By way of example, the teeth have been shown with every tooth bent laterally, and symmetrically.

to opposite sides of the row. I am not limited to symmetrical bending but the bending may be one-sided, nor is it necessary that every tooth should be bent, as only every second, third, fourth, etc., tooth may be bent.

5 Each channelled tooth may have two or more channels, arranged for a coacting tooth or teeth to pass through each of them.

The depth of the channels varies according to 10 requirements.

What I claim as my invention and desire to secure by Letters Patent of the United States is:—

1. A machine for opening, cleaning, carding or like treatment of textile fibers, having in combination two coacting rotatable cylinders, one of said cylinders having approximately tangential teeth thicker at their roots than at their tips, with outwardly facing channels extending from root to tip, and the other cylinder having teeth arranged to pass through the channels of said channelled teeth.

2. A machine for opening, cleaning, carding or like treatment of textile fibers, having in combination two coacting rotatable cylinders, one of said cylinders having approximately tangential gutter shaped teeth whereof the channels face outwards, one side wall of each gutter shaped tooth being tapered to a point, and the other cylinder having teeth arranged to pass through the channels of said gutter shaped teeth.

3. A machine for opening, cleaning, carding or like treatment of textile fibers, having in combination two coacting rotatable cylinders, one of said cylinders having approximately tangential gutter shaped teeth whereof the channels face outwards, the side walls of each gutter shaped tooth tapering to points, and the other cylinder having teeth arranged to pass through the channels of said gutter shaped teeth.

4. A machine for opening, cleaning, carding or like treatment of textile fibers, having in combination two coacting rotatable cylinders, one of said cylinders having approximately tangential gutter shaped teeth whereof the channels face outwards, the side walls of each gutter shaped tooth extending unequal distances beyond the base of the gutter and tapering to points, and the other cylinder having teeth arranged to pass through the channels of said gutter shaped teeth.

5. A machine for opening, cleaning, carding or like treatment of textile fibers, having in combination two coacting rotatable cylinders, one of said cylinders having approximately tangential gutter shaped teeth whereof the channels face outwards, one side wall of each gutter shaped tooth having a reinforcing flange at its edge and being tapered to a point, and the other cylinder having teeth arranged to pass through the channels of said gutter shaped teeth.

6. In a machine for opening, cleaning, carding

or like treatment of textile fibers the combination of a rotatable cylinder having slots in the circumference thereof, approximately tangential teeth on said cylinder having outwardly facing channels, said teeth having lugs and feet joined to said lugs and engaging into said slots, and bars fixed to said cylinder, extending across said feet, whereby said teeth are retained upon said cylinder.

7. In a machine for opening, cleansing, carding or like treatment of textile fibers the combination of a rotatable cylinder having slots in the circumference thereof, approximately tangential teeth on said cylinder having outwardly facing channels, said teeth having lugs and feet joined to said lugs and engaging into said slots, and bars fixed to said cylinder, extending across said feet, whereby said teeth are retained upon said cylinder, said bars having flanges arranged to prevent excessive bending of said teeth.

8. In a machine for opening, cleaning, carding or like treatment of textile fibers the combination of a rotatable cylinder having slots in the circumference thereof, approximately tangential teeth on said cylinder having outwardly facing channels, said teeth having lugs and feet joined to said lugs and engaging into said slots, and bars fixed to said cylinder, extending across said feet, whereby said teeth are retained upon said cylinder, said bars having flanges arranged to prevent excessive outward, inward and lateral bending of said teeth.

9. A machine for opening, cleaning, carding or like treatment of textile fibers comprising two coacting rotatable cylinders, one of said cylinders having approximately tangential teeth with outwardly facing channels extending from root to tip, and the other cylinder having teeth arranged to pass through the channels of said channelled teeth.

10. A machine for opening, cleaning, carding or like treatment of textile fibers comprising two coacting rotatable cylinders, one of said cylinders having approximately tangential teeth with outwardly facing channels extending from root to tip, and the other cylinder having teeth arranged to pass through the channels of said channelled teeth.

11. A machine for opening, cleaning, carding or like treatment of textile fibers comprising two coacting rotatable cylinders, one of said cylinders having approximately tangential teeth with outwardly facing channels extending from root to tip and the other cylinder having laterally bent teeth arranged to pass through the channels of said channelled teeth.

RUDOLF SETZER.
